TIMER

Lewis W. Coren, Chicago, Ill., assignor to Zenith
Electric Company, Inc., Chicago, Ill., a cor-
poration of Illinois

Application June 4, 1935, Serial No. 24,788

6 Claims. (Cl. 200—90)

This invention relates to circuit control apparatus, and has for an object the provision of a novel and an improved control device for making and breaking electrical circuits at predetermined periodic intervals.

Another object of the invention is the provision of such a device which is adjustable, whereby the controlled circuit may be completed or interrupted at variable predetermined intervals.

10 A further object of the invention is the provision of such a time control device which may be automatically reset, whereby the completion or interruption of the circuit may be repeated at desired intervals.

15 Another object of the invention is the provision of a time control device of simple construction and operation, but positive and reliable.

Other objects of the invention include the provision of the novel arrangements and combinations of elements as hereinafter described and claimed, and as illustrated in the accompanying drawings, in which

Fig. 1 is a front elevation of a time control device embodying the features of the invention;

20 Fig. 2 is a side elevation of the device shown in Fig. 1, at a slightly different scale, and shows the relation of the timer control switch and its driving means in a set position;

Fig. 3 is a fragmentary front elevation with parts broken away, showing the timer control switch in its closed position;

25 Fig. 4 is a view similar to Fig. 3, showing the timer control switch in its open position;

Fig. 5 is a fragmentary vertical cross section of the time control device showing the driving means coupled in driving relationship with the operating means for the time control switch;

30 Fig. 6 is a fragmentary cross section taken substantially along the lines 6—6 of Fig. 2;

Fig. 7 is a cross section taken substantially along the lines 7—7 of Fig. 2;

35 Fig. 8 is a fragmentary section taken substantially along the lines 8—8 of Fig. 7; and

Fig. 9 is a schematic wiring diagram of the novel time control device.

40 Illustrative of the invention, circuit switch means 11 are provided as shown in Fig. 9, for controlling the supply of electrical energy from a terminal or binding post 12, and a terminal or binding post 13, to a terminal or binding post 14, whereby a load having one side 15 connected to the terminal 14, and its other side 16 connected to a terminal or binding post 17, may be electrically connected to, and disconnected from, a 45 supply line with one side 18 connected to the

terminal 12, and its other side 19 connected to the terminal 17.

The switch means 11 is associated with electro-magnetic or solenoid means 21, which is controlled by timer switch means 22 that is operable from driving means M for operating the switch means 11 at adjustable, predetermined intervals. For that purpose, the solenoid means and the motor are connected in parallel by conductors 23, and the parallel connected solenoid means and motor are connected across the terminals 13 and 17 by a conductor 24 to the terminal 17 and a conductor 25 to one terminal of the timer switch means 22, and a conductor 26 from the other terminal of the timer switch means 22 to the terminal 13. A main control or pilot switch 27 is connectible between terminals 12 and 13 by conductors 28 and 29, respectively, for controlling the energy supply of the novel timer apparatus.

45 For assembling the circuit switch means 11, the solenoid means 21, the timer switch means 22, and the driving means M in operative relationship, a substantially rectangular panel 31 is provided with an aperture 32 near the upper end and centrally of the panel, an aperture 33 spaced laterally and below the aperture 32, a pair of spaced studs or stops 34 and 35 projecting from the front face of the panel 31 between the apertures 32 and 33, and a slot or cut away portion 36 in the lower end of the panel for receiving a terminal strip 37 carrying the terminals 12, 13, 14, and 17, and secured as at 38 to the panel 31.

50 At the rear face of the panel 31, the driving means M, including an electric motor 39 and suitable speed reducing mechanism 39' therefor, is carried on a mounting plate 41 supported in spaced relationship with the panel 31 by spacers 42 secured as at 43 at their opposite ends to the panel 31, and the plate 41, and has a drive shaft 44 extending through the plate 41 toward the panel 31. The outer end of the shaft 44 is supported or journaled in a bracket 45 secured as at 46 to the plate 41.

55 The driving means M is adapted to drive a friction clutch element 47 which is fixed on the shaft 44 between the bracket 45 and the plate 41, and which may take the form of a soft rubber ring 48 between retaining rings or discs 49 at opposite sides thereof. Another clutch element 51 like the clutch element 47 with its soft rubber ring 52 held between retaining rings or discs 53 is carried on a sleeve 54 having an enlarged portion 55 intermediate its ends for spacing the clutch element 51 from a disc 57 which, with the clutch element 51, is fixed on the sleeve and 55

which is connected to the clutch element 51 by a pin 58, as shown best in Fig. 7.

The sleeve 54 carrying the clutch element and the disc 51, is fixed on the inner end of a shaft 59 for rotation therewith, the center portion of which is embraced by a sleeve 61 having an end flange 62 abutting the adjacent end of the sleeve 54. The shaft and its embracing sleeve 61 are receivable in the aperture 32, so that the clutch element 51 and the disc 51 are aligned with the clutch element 47 and are at the rear face of the panel 31, the shaft projecting beyond the front face of the panel 31 and carrying at that end a sleeve 63 which is fixed on the shaft for rotation therewith, and which has an end flange 63' spaced from the panel 31 by a spacing sleeve 64 on the sleeve 61, and a threaded shank portion 65 with an unthreaded shank portion 65' intermediate the threaded portion 65 and the flange 63'. The threaded portion 65 of the sleeve 63 has a flat side 66 for facilitating drivingly coupling the shaft to switch operating means for the timer switch means 22, as will presently be described.

25 In order to drive the shaft 59 from the shaft 44 of the driving means M, the clutch elements 47 and 51 cooperate with a reciprocable clutch element 67 in the form of a rotatable disc having a rough surface 68 and carried on a plunger 69 between spaced collars 71 and 72, the disc being normally yieldably urged against the lower face of the collar 71 by a coil spring 72' encircling the plunger between the collar 72 and the lower face of the disc 67. The reciprocable plunger 69 is guidably receivable in apertures 73 in the ends of spaced brackets 73' secured as at 74 to the rear face of the panel 31 and extending rearwardly therefrom, respectively above and below the shaft aperture 32, whereby reciprocation of 40 the plunger 69 will cause the rough surface 68 of the disc 67 to engage and disengage the rubber rings 48 and 52 on the shafts 44 and 59, respectively.

As shown more particularly in Figs. 2, 5, and 45 6, the lower end of the plunger 69 is supported on a block 75 of insulating material fixed to and reciprocable with the upper end of the core or armature 76 of the solenoid 21 for operating the clutch just described. The solenoid includes, in 50 addition to its armature or core 76, a solenoid winding 77 and a magnetic frame 78 having vertical mounting strips 79 secured as at 81 to the rear face of the panel 31, and a horizontal strip 82.

55 The solenoid 21 is adapted to operate the circuit switch means 11 which comprises a pair of switch contact members 83 carried on an insulating plate 84 secured on the horizontal strip 82, one of the contact members 83 being connected by a conductor 85 to the terminal 14, and the other contact member 83 being connected by a conductor 86 to the terminal 12. A switch member or arm 87 is carried on the shank of a pin 88 in the insulating block 75, and is arranged 60 on the pin between a pin flange or head 89 and the upper end of a coil spring 91, the lower end of which engages an abutment 92 on the shank of the pin 88, whereby the spring yieldably urges the switch arm 87 against the pin head 89. That 65 switch arm 87 is adapted to span between, and contact with, the switch contact members 83, whereby to close the switch when the solenoid 21 is energized.

As shown in Fig. 9, the switch means 11 also 70 75 comprises another pair of contact members 93

on the insulating plate 84 at the opposite side of the insulating block 75 from the contact members 83. Those contact members 93 cooperate with a switch arm 94, like the switch arm 87, but carried at the opposite side of the insulating block 75 for electrically connecting the contact members 93 together when the solenoid 21 is energized. One of the contact members 93 is connected by a conductor 95 to the conductor 26, and the other contact member 93 is connected by a conductor 96 to the conductor 86. In that manner, the switch means 11 shunts the solenoid 21 and the driving means M, whereby upon energization of the solenoid and the closing of the switch means, the starting or initial energy requirements of the solenoid and driving means in excess of that required to maintain their energization, may be utilized in supplying the load.

As already explained, the timer switch means 22 controls the energy supply of the solenoid 21 and the driving means M. That timer switch means 22 comprises, as seen in Figs. 2, 3, and 4, a contact member 101 carried on a bracket 98 secured as at 99 to the rear face of the panel 31, and a contact member 101 carried by and insulated from a swingable U-shaped member 102 having its upstanding arms 103, respectively pivoted as at 104 to the rear face of the panel 31, and an arm 105 spaced therefrom and secured as at 106 to the rear face of the panel 31. The contact member 101 is normally held in engagement or electrical contact with the contact member 97 by a toggle arm or link 107 connected as at 108 to the U-shaped member 102, the link 107 having a portion 109 loosely receivable in a transverse aperture 110 of a pin 112 carried between spaced arms 113, which are fixed on the rear end of a shaft 114 journaled intermediate its ends in the aperture 33. A spring 115 on the link 107 resiliently holds the spaced arms 113 and the U-shaped member 102 in their respective positions for maintaining the contact member 101 in its closed and open positions with respect to the contact member 97.

At the outer end of the shaft 114, and outwardly of the panel 31, a switch operating arm 116 is fixed on the shaft 114 and projects therefrom to a position between the limiting studs 34 and 35. By moving the arm 116 from the stud 34 to the stud 35, the switch means 22 is opened and 50 by moving the arm back to its normal position of engagement with the stud 34, the switch means 22 is closed. An object of this invention is so to operate the timer switch means 22 that the solenoid 21 will operate the circuit switch means 11 at predetermined intervals, and to provide means for automatically resetting the apparatus, whereby the cycle may be repeated.

To that end, a disc 117 is calibrated and provided with indicia 118 to provide an indicating 60 dial. That disc or dial has a shaft aperture 119 therein with a flat side 121, so that it may be carried on the shaft 63 to rotate therewith. The disc 117 is provided with a pin 122 normally engaging the arm 116 when it is in engagement 65 with the stud 34 and the switch means 22 is closed. The disc is so calibrated that the indicia 118 indicate the times required for the driving means M through the clutch means to rotate the disc through the respective arcs defined by the 70 calibrations on the disc.

Associated with the disc 117 is an arm 123 receivable on the unthreaded portion 65' of the sleeve 63 between the disc 117 and the flange 63', and extending radially to the periphery of the 75

disc where the arm is provided with a pointer or finger 124 cooperating with the indicia 118 for indicating time intervals. Intermediate the ends of the arm, a lug or finger 125 is provided for engaging the switch operating arm 116 to move it in a switch opening direction. The disc 117 and the arm 123 may be clamped together for rotation with the sleeve 63 and the shaft 59 by a knurled nut 126 threadingly engaging the threaded portion 65 of the sleeve 63.

By loosening the nut 126, the arm 123 may be swung about the shaft 59 until the pointer 124 indicates on the disc the time interval desired for operating the circuit switch means 11, whereupon the nut 26 may be tightened to clamp the arm 123 between the disc 117 and the flange 63' of the sleeve 63, and thereby to cause the arm 123 to rotate with the disc 117 and the shaft 59.

A spiral spring 127 is arranged about the sleeve 54 between the clutch member 51 and the disc 57, and is anchored at its inner end to the pin 58. The outer end of the spring is anchored as at 128 to the upper plunger or arm 73'. In that manner, the disc 117 is yieldably held in its normal position with the pin 122 yieldably holding the switch operating arm 116 against the limiting stud 34, whereby to hold the timer switch means 22 closed.

Before closing the main control switch 27, the knurled nut 126 may be loosened and the arm 123 swung about the shaft 59 toward or away from the pin 122 until the pointer 124 registers with the desired time interval of the indicia 118 on the dial or disc 117 whereupon the nut 126 is tightened to lock the arm 123 for rotation with the disc 117 and the shaft 59. Upon closing the main control switch 27 after such adjustment of the arm 123, the parallel connected solenoid 21 and driving means M are energized from the line terminal 12, the conductor 28, switch 27, the conductor 29, the terminal 13, the conductor 26, the closed timer switch 22, and the conductor 25 to the solenoid and driving means, and therefrom to the other line terminal 17.

The energization of the solenoid 21 closes the switch means 11, thereby closing the circuit from the line terminal 12 through the conductor 86, switch contact members 83, the conductor 85 to the load terminal 14, and therefrom through the load conductor 15 and back through the load conductor 16 to the other line terminal 17. Upon energization, the solenoid 21 also raises the plunger 69 to cause the rough surface of the clutch member 67 to engage the clutch elements 48 and 51, whereby to couple the driving means M to the shaft 59 for driving the latter.

As the shaft 59 is thus rotated against the action of the spiral spring 127, the dial or disc 117 and the arm 123 are rotated in a counter-clockwise direction, as viewed in Figs. 1, 3, and 4, causing the pin 122 carried by the dial to disengage the switch operating arm 116 and the lug 125 on the arm 123 to move toward engagement with the switch operating arm 116. As the time indicated on the dial 117 by the pointer 124 elapses, the lug 125 engages the switch operating arm 116 and moves it from the limiting stud 34 to the limiting stud 35, thus rotating the shaft 114 in a direction to swing the switch contact member 101 out of engagement with the switch contact member 97, whereby to open the timer switch 22.

The opening of the timer switch 22 interrupts the circuit including the driving means M and the solenoid 21, which are thus deenergized,

thereby permitting the solenoid core 76 to return to its lower position. When the core 76 is thus released by the solenoid, the switch arms 87 and 84 disengage the contact members 83 and 93, respectively, of the switch means 11, thus interrupting the supply of energy to the load and assisted by the gravity, the spring 72' lowers the plunger 69 to move the clutch member 67 from operative engagement with the clutch elements 47 and 51.

When the clutch element 51 is disengaged by the clutch member 67, the shaft 59 is free to rotate and the spring 127 rotates the shaft as well as the dial 117 and the arm 123 in a clockwise direction, as viewed in Figs. 1, 3, and 4. That reverse rotation of the shaft 59 causes the lug 125 on the arm 123 to disengage the switch operating arm 116 and to return to its original or reset position. During the return movement of the lug 125, the pin 122 carried by the disc 117 engages the switch operating arm 116 and swings it from the limiting stud 35 to the limiting stud 34, thus rotating the shaft 114 to close the timer switch 122. Upon closing the timer switch, the foregoing cycle will be repeated and will be continued as long as the main control switch 27 remains closed.

While I have described a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A control apparatus for making and breaking an electrical circuit, comprising a circuit control switch, a timer switch, timer switch operating means, driving means for said operating means, clutch means for connecting said driving means to said switch operating means, and electromagnetic means controlled by said timer switch for operating said circuit switch and said clutch means.

2. A control apparatus for making and breaking an electrical circuit, comprising a circuit switch, a timer switch, operating means for opening and closing said timer switch, driving means for driving said operating means, said driving means being controlled by said timer switch, clutch means for connecting said driving means to said operating means, and electromagnetic means controlled by said timer switch for closing said circuit switch and for operating said clutch means to connect said driving means to said operating means whereby said operating means opens said timer switch to cause said electromagnetic means to open said circuit switch.

3. A control apparatus for periodically making and breaking an electrical circuit, comprising a circuit switch, a timer switch normally closed, switch operating means for opening said timer switch, driving means controlled by said timer switch for driving said switch operating means whereby to open said timer switch at predetermined intervals, clutch means for connecting said driving means to said switch operating means, other driving means controlled by said clutch means for driving said switch operating means whereby to close said timer switch after it has been opened, and means controlled by said timer switch for closing said circuit switch when said timer switch is closed and for opening said

circuit switch when said timer switch is opened, and means for operating said clutch means to cause said other driving means to close said timer switch after it has been opened by the first said driving means.

5. 4. In a control apparatus for periodically making and breaking an electrical circuit, a normally closed timer switch, switch operating means for said timer switch, driving means controlled by 10 said timer switch for driving said switch operating means, and electromagnetically operable clutch means controlled by said timer switch for 15 drivingly connecting said driving means to said switch operating means.
15. 5. In a control apparatus for periodically making and breaking an electrical circuit, a normally closed timer switch, switch operating means for opening said timer switch, driving means controlled by said timer switch for driving said 20 switch operating means to open said timer switch after a predetermined time interval, a friction clutch element driven by said driving means, a friction clutch element for driving said switch operating means, a clutch member having a 25 rough surface engageable with both said clutch

elements, whereby said driving means will drive said switch operating means, and electromagnetic means controlled by said timer switch for operating said clutch member.

6. In a control apparatus for periodically making and breaking an electrical circuit, adjustable indicating means for adjustably indicating the periodicity of control for an electrical circuit, means for driving said indicating means in accordance with the indicated periodicity, means 10 for resetting said indicating means to its adjusted position after it has been driven by the driving means, and a timer switch controlling said driving means and operable by said adjustable indicating means, said timer switch including 15 a switch contact member, a shaft having a switch operating arm thereon, a pivoted U-shaped member having a switch contact member thereon, toggle connecting means connecting said shaft and said U-shaped member whereby 20 said U-shaped member is operable from said shaft for causing the last said switch contact member to engage and disengage the first said contact member.

LEWIS W. COREN. 25
